(57) **CLAIM**

The ornamental design for medical gown with tie straps, as shown and described.

DESCRIPTION

FIG. 1 is a front elevation view of the medical gown with tie straps, showing the loose front ends of the long and short straps.

FIG. 2 is a rear elevation view of the gown showing the fixed rear end of the long strap adjacent one edge of the open back of the gown.

FIG. 3 is a right side elevation view of the gown showing the long and short straps.

FIG. 4 is a left side elevation view of the gown.

FIG. 5 is a top plan view of the gown showing the long strap over the right shoulder.

FIG. 6 is another right side elevation view showing the loose end of the shoulder strap moved away from the body; and, FIGS. 7-12 are similar to FIGS. 1-6, except the long and short straps are on the opposite side of the gown.

No claim is made to the bottom view of the gowns shown in FIGS. 1-12.

The dash-dash broken lines in the drawings are included for the purpose of illustrating subject matter that forms no part of the claimed designed. The dash-dot-dash broken lines shown define the bounds of the claimed design and form no part thereof.

1 Claim, 6 Drawing Sheets
